UNITED STATES PATENT OFFICE.

WILSON HEMINGWAY, JR., OF VICKSBURG, MISSISSIPPI, ASSIGNOR TO THE ELECTRO-LOCK MANUFACTURING COMPANY, OF VICKSBURG, MISSISSIPPI, A CORPORATION OF MISSISSIPPI.

IGNITION SYSTEM AND SWITCH THEREFOR.

Application filed April 28, 1924. Serial No. 709,696.

The principal purpose of this invention is to provide more efficient and dependable theft protection for automobiles by making it practically a physical impossibility for 5 the owner or operator to switch off the ignition system in stopping the motor without first actuating an automatic lock mechanism associated with the switch and functioning, in locked position, to prevent reestablish- 10 ment and use of the ignition system except by a person having a proper key.

To this end the invention consists essentially in the provision of a switch included in the ignition system in such manner as to 15 constitute the sole means of disconnection between the source of current supply and the remaining components of the system such as the induction coils, spark plugs, etc., suitable locking means being associated with the 20 switch and arranged to function automatically at an intermediate point in the actuation of the switch from closed to open position.

A further purpose of the invention is to 25 provide means included in the switch for making and breaking the main generator circuit and the generator shunt field circuit simultaneously with establishment and disruption of the ignition system or circuit.

A still further purpose of the invention is to provide a switch having the operating parts thereof so assembled and encased as to prevent unauthorized access to or manipulation of such parts in the closed position 30 of the switch while permitting disassembly of the parts to be readily effected in the unlocked or open position of the switch.

A still further purpose of the invention is to provide a casing for the induction coil 35 assembly including means enclosing the coil terminal connected to the battery or other source of current supply in such manner as to prevent access thereto.

Other purposes, advantages and characteristic features of the invention will be 40 more readily understood from the following detailed description and accompanying drawings; in which

Fig. 1 is a diagrammatic view of an ignition system including my invention.

Fig. 2 is a partly diagrammatic view showing the switch mechanism in front elevation

and the manner in which such mechanism is connected to the generator and the storage battery.

Fig. 3 is a longitudinal sectional view of the improved switch, and

Figs. 4, 5 and 6 are fragmentary views similar to Fig. 3, but showing the switch members in different positions.

Figure 7 is a transverse sectional view taken along line 7-7 of Figure 4.

Preparatory to entering upon a detailed description of the subject matter disclosed in the present application I may state that the same is a modification of that disclosed in companion application, Serial Number 709,695, the subject matter of the present application being designed more particularly for automobiles other than those of the Ford type. Referring now more particularly to the switch structure illustrated in Figs. 3 to 7, inclusive, reference character 5 designates a casing in which the operating parts of the switch are enclosed. This casing is 50 preferably composed of hardened steel or other metal difficult to cut or drill through in an effort to gain access to the interior of the casing. At one end the casing is closed by an inserted metal knob 6 carried by and securely anchored to one end of a cable 7 enclosing a conductor 8. The knob 6 is in abutting engagement with one side of a ring 9 fastened to the inner wall of the casing by pins 10 or other suitable means. The knob is held to the casing by means of a nut 11 fitting the opening in the ring 9 and threadedly engaged with a reduced or neck portion 12 projecting inwardly from the knob and formed integral therewith. At its inner end the nut 11 is equipped with a marginal flange 13 engaging the inner side of the ring 9. A screw 14 threaded through the nut and terminating in a smooth tip or stem 15 entering a suitable socket 16 formed in the knob serves to lock the knob and nut against relative rotation necessary to separation thereof. The end of the conductor 8 shown in Fig. 2 extends inwardly through the neck 11 and terminates in an enlarged flat head 17 resting against the inner end of the neck and contacting with a copper disk 18. The disk 18 is centered within an insulating ring 19 which serves as a spacer

between the nut 12 and insulating block 20 carrying a pair of contacts 21 and 22. The contact 21 is made of sufficient length to extend entirely through the block 20 and to project beyond one face of the block into engagement with the disk 18. The opposite end of the contact 21 and the corresponding end of the contact 22 are projected a slight distance beyond the opposite face of the block 20 for engagement with the movable contact hereinafter referred to. The inner or embedded end of the contact 22 is secured, preferably by threaded engagement, to the inner end of a binding post 23. This post extends laterally through the block 20 and through an insulated bushing 24 in the side wall of the casing 5 and is equipped at its outer end with binding nuts 25. Carried by the insulating block 20 at points intermediate contacts 21 and 22 are a second pair of contacts designated 26 and 27 secured respectively to suitable binding posts 28 and 29 projecting outwardly from the casing 5.

25 The central portion of the block 20 is hollowed out to provide a socket 30 in which is received one of the cylindrical ends of an insulating stem 31, the opposite cylindrical end of which is disposed in a central opening formed in a second insulating block 32 spaced from the block 20 through the medium of an interposed insulating shell 33. The stem 31 is shaped to provide a widened central portion and inclined surfaces 34 and 35 sloping downwardly in opposite directions from the central toward the cylindrical end portions of the stem. This stem is hollowed out to provide a central longitudinally extending bore 36 housing therein a spring 37 having one end bearing against the closed end of the bore and the other end bearing against the opposing or bottom wall of the recess 30. This stem serves as the actuator for the movable contact of the switch which comprises a ring shaped casing 38 open at its inner periphery and containing a coil spring 39 closely embracing the stem 31 as shown to advantage in Fig. 2.

50 The end of the casing 5 remote from the knob 6 is provided with an inserted bushing 40 secured to the casing by a pin 41 passing through aligned openings formed in the bushing and in the casing. This pin is widened at an intermediate point to provide a shoulder 42 bearing against the inner wall of the casing and serving to prevent the pin from being drawn outwardly through the opening formed in the casing. The pin is prevented from being displaced inwardly by reason of the fact that the inner end of the pin engages the outer surface of a lock barrel 43 slidably mounted in the bushing 40 and capable of movement to the left from the position shown in Fig. 3. In order to

limit the sliding movement of the barrel and prevent complete separation thereof from the casing 5 the outer surface of the barrel is provided with an elongated recess 44 in which is engaged the inner end of a stop pin 45 suitably carried by the bushing 40 and casing 5. The locking mechanism enclosed within the barrel 43 includes a spring projected bolt 46 adapted to automatically enter an opening 47 in the bushing 40 when the lock barrel is in its innermost position as shown in Fig. 3.

It may be stated here that the position of parts disclosed in Fig. 3 is that assumed when the switch is in the locked or open position. In this position of the switch the various contacts carried by the insulator block 20 are disconnected from one another so that there can be no flow of current through the switch. When it is desired to close the switch the lock bolt 46 is retracted from the opening 47 by means of a suitable key 48 and the stem 31 and lock barrel 43 are then free to travel to the left under the influence of the spring 37 until the right hand end of the slot 44 contacts with the stop pin 45 to arrest further movement of the lock barrel. During this movement of the stem 31 the movable contact 38 remains in position against the inner face of block 32 until the central portion of the stem has passed through the spring 39 to the extent shown in Fig. 4 at which time the pressure of the spring 39 acting on the inclined surface 35 will cause the movable contact to snap to the right into engagement with the contacts carried by the block 20, as shown to advantage in Fig. 5. In this closed position of the switch, current supplied to the binding post 23 will pass from contact 22 through contacts 38, 21 and copper disk 18 to the conductor 8 through which it is conveyed to the induction coils as later set forth. In like manner current supplied to the binding post 28 will pass through the contact 26, movable contact 38 and contacts 22 and 27 to the binding posts 23 and 29.

In practice, the switch mechanism of my invention is embodied in a system of distribution as shown to advantage in Figs. 1 and 2. In these figures it will be noted that the end of the cable 7 opposite that secured to casing 5 is anchored within the neck portion 49 of the casing 50 enclosing the induction coil or transformer assembly 51. At this end of the cable the conductor 8 is connected, through the primary winding of the induction coil and a suitable resistance 52, to the breaker or interrupter points 53. The high tension terminal 54 of the induction coil is connected in the usual manner to the distributor 55. Current for the induction coil is supplied from a suitable storage battery 56 having its insulated terminal connected by a lead 57 to the binding

post 23 of the switch, the remaining terminal of the storage battery being grounded. The binding posts 28 and 29 are connected by leads 28' and 29' to the main and 5 shunt field circuits of the generator 58 so that the making and breaking of the generator circuits will occur simultaneously with the making and breaking of the ignition circuit or system. It is, however, only necessary to provide this latter arrangement for 10 use on certain automobiles using a certain type of shunt generator which, if left connected to the battery after the ignition circuit is broken, might cause the shunt winding to be damaged or cause the storage battery to be completely discharged. When 15 the movable contact 38 of the switch is in the position shown in Fig. 5 current from the battery flows through contacts 22, 38, 21 and disk 18 to the conductor 8 connected to the primary winding of the induction coil. The bridging of the contacts 26 and 27 by the movable contact 38 also serves to 20 simultaneously close the generator circuits as and for the purpose previously set forth. When it is desired to disrupt the ignition circuit, this is accomplished by pushing or 25 forcing the lock barrel 43 inwardly to the right from the position shown in Fig. 5 to the position shown in Fig. 3. This barrel being in engagement with the adjacent end of the stem 31 causes the latter to move in the same direction until the central portion 30 of the stem has passed through the spring 39 to the extent shown in Fig. 6 at which time the pressure of the spring on the inclined surface 34 will cause the movable contact 38 of the switch to snap to the left to assume 35 the position shown in Fig. 3, thus breaking the connection between the various contacts 40 carried by the block 20. The switch is so constructed that during the movement of the lock barrel and stem 31 to the right from the position shown in Fig. 5 the bolt 46 will 45 reach and enter the opening 47 just before the central portion of the stem reaches the position shown in Fig. 6 so that the locking of the switch will take place slightly earlier than the actual separation of the 50 switch contacts, thus making it practically a physical impossibility to open the ignition circuit without first actuating the locking mechanism which functions to prevent re-establishment and use of the circuit, except 55 by authorized persons. In further explanation of this feature of the invention, it is pointed out that the opening 47 is made sufficiently larger than the bolt 46 so that the latter after entering the opening is capable 60 of a limited movement therein sufficient to permit the lock barrel and the stem 31 to continue to travel to the right until the central portion of the stem reaches the position shown in Fig. 6 at which time opening of 65 the switch occurs as previously described.

The permissible movement of the bolt 46 in the opening 47 is not, however, sufficiently great to permit retrograde movement of the stem to the extent necessary to effect closure of the switch. 70

It will be noted, as disclosed in Fig. 3, that the operating parts of the switch are assembled and encased in such manner that unauthorized manipulation or access to such parts is rendered practically impossible in 75 the closed position of the switch. In this connection it is pointed out that the outer end of the pin 41 holding the bushing 40 to the casing 5 is flush with the outer surface of the said casing and this, in conjunction with the shoulder 42 with which said pin is provided serves to render it impossible to pull the pin outwardly for the purpose of releasing the bushing for removal. Displacement of the pin inwardly is prevented 80 by reason of the fact that the inner end of the pin is in engagement with the outer surface of the lock barrel 43 in both the open and closed positions of the switch. Removal of the barrel 43 from the bushing 40 is prevented in the locked position of the switch by engagement of the bolt 46 in the opening 47. The knob 6 at the opposite end of the casing is prevented from being disengaged from the nut 11 by means of the screw 14 which is so positioned as to be accessible upon removal of the parts between the nut 11 and the remote end of the casing. However, disassembly of the switch members is rendered a comparatively easy matter for 85 persons having a proper key to the lock barrel 43. It is simply necessary in the locked position of the switch to first remove the stop pin 45 so that when the key 48 is inserted in the lock barrel and manipulated 90 to withdraw the bolt 46 from the opening 47, the lock barrel may be completely removed from the bushing 40. The pin 41 can then be driven inwardly through the aligned openings in the casing and bushing to free 95 the latter for removal from the casing. On removal of the bushing 40 it is obvious that insulating block 32, shell 33, stem 31 and movable contact 38 are free to be removed through the left hand end of the casing. The binding post 23 is then disengaged 100 from the contact 22 and removed to permit the block 20, insulating ring 19 and copper disk 18 to be withdrawn from the casing. Removal of these latter parts exposes the 105 inner end of the pin 14 which is removed prior to unscrewing nut 11 from the neck 12. The ring 9 is preferably permanently fastened to the casing by the pins 10 but if desired, the latter may be merely a tight fit in the aligned openings in the casing and ring so as to be capable of being driven inwardly and removed subsequent to removal 110 of the nut 11 and knob 6. It will, therefore 115 be evident that the switch, while secured 120 to the body of the automobile, is rendered 125 incapable of being opened or closed except by 130 authorized persons.

against disassembly in locked position may be readily taken apart upon release and removal of the locking mechanism.

In the foregoing I have described what I now consider to be preferred embodiment of my invention and it is to be understood that various changes may be resorted to in the construction, combination and arrangement of parts without departing from the spirit and scope of the invention as designed in the appended claims.

What I claim as my invention:

1. A locking device comprising a switch and a locking mechanism with means where-
15 by the locking device operates at a time not later than the instant of opening the switch.

2. In combination, a switch, switch closing means normally tending to urge the switch to closed position, a member movable to open 20 the switch against the resistance of the switch closing means, and a lock mechanism functional to prevent retrograde movement of said member when the latter is moved in a switch opening direction, said lock 25 mechanism being arranged to become effective automatically at a time not later than the opening of the switch.

3. In combination, a switch including a member reciprocal to open and close said 30 switch and a lock mechanism functional to prevent retrograde movement of said member when the latter has traveled a predetermined distance in a switch opening direction, said locking mechanism becoming effective 35 at a time not later than the instant of opening the switch.

4. In combination, a switch including sta-
tionary and movable contacts, a member re-
ciprocal to engage or separate said contacts 40 to thereby close or open the switch, means normally tending to urge said member to a switch closing position, means for moving said member to a switch opening position, and means functional during the last men-
45 tioned movement of said member to lock the member against retrograde movement at an instant not later than the opening of the switch.

5. In combination, a switch including sta-
tionary and movable contact means, a recip-
rocal member provided with inclines engage-
able with the movable contact means to shift 50 same into or out of engagement with the sta-
tionary contact means to thereby close and
open the switch upon reciprocation of said
member, spring means normally tending to move said member in a direction to engage the movable and stationary contact means to thereby close the switch, a follower oper-
60 able to move said member in a reverse direc-
tion to thereby open the switch against the resistance of said spring means, and means for locking said follower in switch opening position.

6. In combination, a switch including sta-

tionary and movable contact means, a recip-
rocal spindle provided with oppositely slop-
ing inclines engageable with the movable contact means to shift same into or out of engagement with the stationary contact 70 means upon reciprocation of the spindle, and means for locking the spindle in a contact separating position, said locking mechanism becoming effective at a time not later than the instant of opening the switch. 75

7. In combination, a switch including sta-
tionary and movable contact means, a recip-
rocal spindle provided with oppositely slop-
ing inclines engageable with the movable contact means to shift same into or out of engagement with the stationary contact 80 means upon reciprocation of the spindle, and means for locking the spindle in a contact separating position, said means being ar-
ranged to become effective automatically at 85 a time not later than the instant of sepa-
rating the contacts.

8. In combination, a switch including sta-
tionary and movable contacts, a reciprocal 90 spindle provided with means for actuating the movable contacts to engage said contacts with the stationary contacts when the spindle is moved in one direction to thereby close the switch and to separate the movable and stationary contacts on movement of the spindle in the reverse direction to thereby open the switch, means normally tending to move said spindle to a switch closing position, a movable follower engageable with one 95 end of the spindle and functional to shift the spindle to a switch closing position and means for locking the follower and spindle in a switch opening position, said locking mechanism becoming effective at a time not later than the instant of opening the switch. 100

9. The combination of a switch including an enclosing casing, an actuating member reciprocal in said casing to effect opening and closing of said switch and a lock mech-
anism contained within the actuating mem-
ber and including a spring projected bolt 110 adapted to automatically enter an opening in the casing when the actuating member has been moved a predetermined distance in a switch opening direction and at a time not later than the actual opening of the switch. 115

10. A locking device comprising in combi-
nation, a switch, and a locking mechanism 120 cooperating therewith comprising means whereby upon movement of said switch to its open po ition, said locking mechanism auto-
matically moves to its locked position sub-
stantially at the instant of separation of said contacts.

11. A locking device comprising in combi-
nation a circuit controlling device and a lock 125 mechanism cooperating therewith, compris-
ing means whereby upon movement of the circuit controlling device to off position said locking mechanism automatically moves to 130

its locked position, substantially at the initiation of movement of the circuit controlling device to said off position.

12. A switch comprising spaced stationary contacts, a movable contact, means for shifting the movable contact into or out of engagement with the stationary contacts comprising a reciprocable spindle having inclined cam portions and spring means carried by the movable contact and coacting with said cam portions to snap the latter into engagement with the stationary contacts on movement of the spindle in one direction and to separate the movable contact from the stationary contacts on movement of the spindle in the opposite direction and locking means functioning automatically during the second mentioned movement of the spindle to lock the stationary and movable contacts in separated position.

13. A switch comprising spaced stationary contacts, a movable contact for bridging the stationary contacts when engaged therewith, a reciprocable spindle, coacting means carried by the movable contact and spindle to snap the movable contact into engagement with the stationary contacts on movement of the spindle in one direction and to snap the movable contact out of engagement with the aforesaid stationary contacts on movement of the spindle in the opposite direction and means functioning automatically to lock the spindle against return movement when shifted in the direction to separate the movable contact from the stationary contacts, said means being arranged to act at an instant not later than the actual separation of the contacts.

14. A switch comprising spaced stationary contacts, a movable contact for bridging the stationary contacts when engaged therewith, a reciprocable spindle, coacting means carried by the spindle and movable contact for snapping said movable contact into engagement with the stationary contacts on

movement of the spindle in one direction and to snap the movable contact out of engagement with the stationary contacts on movement of the spindle in the opposite direction, a spring normally tending to move the spindle in a direction to effect engagement of the movable and stationary contacts, a follower for moving the spindle in the opposite direction and against the resistance of the spring to effect separation of the contacts and means for automatically locking the follower and spindle in contact separating position, said means acting during and in such timed relation to the contact separating movement of the spindle that the locking of the spindle against reverse movement occurs at an instant not later than the actual separation of the contact.

15. A switch comprising spaced stationary contacts, a movable contact for bridging said stationary contacts when engaged therewith, a reciprocable spindle, coacting means carried by the spindle and movable contact to snap the movable contact into or out of engagement with the stationary contacts dependent on the direction in which the spindle is moved, a spring arranged to urge the spindle in one direction to engage the stationary and movable contacts, means for moving the spindle in the opposite direction against the resistance of said spring to effect separation of the contacts, said means embodying a locking mechanism including a bolt of the automatically projected type and a casing enclosing the aforementioned parts and provided with an opening in which said bolt automatically engages during movement of the spindle in a contact separating direction and at an instant not later than the actual separation of the contacts.

In testimony whereof I hereunto affix my signature.

WILSON HEMINGWAY, JR.
